BATHTUB

Robert Mueller, Decatur, Ill.

Application July 23, 1934, Serial No. 736,601

3 Claims. (Cl. 4—173)

The present invention relates to bath tubs.

It has for its object to provide a non-slip bath tub, and further, to give such a construction of the front wall or apron of the tub as will permit the user to take a position outside of the tub for manipulating the faucets or bending over the tub with greater ease than with tubs now in use.

In the drawing herewith I have illustrated my invention, and in said drawing:

10 Figure 1 is a perspective view of a portion of a tub, showing my invention,

Figure 2 is a sectional view through a portion of the bottom and end wall of the tub showing the waste outlet in elevation.

15 Referring to the drawing by numbers, like numbers indicating like parts in the several views, 10 indicates the tub proper, which may be of any desired material, the form of tub here shown being the usual metal enameled tub characterized 20 by the usual side and end walls and the outer apron 11.

The walls of the tub extend downwardly to the bottom, to which they are joined by the curved sections 12, said sections 12 forming an inwardly 25 turned substantially horizontal rim or edge extending, as here shown, completely around the tub.

The tub bottom 13 is sunken, as shown, preferably from the edge of the bottom section 12 to 30 form a substantial recess, as clearly shown in the drawing. In Figure 1 the recess in the bottom extends substantially the full length of the tub, being inset from and surrounded by the bottom section 12, forming a marginal offset between the 35 tub walls and the recess. It will be noted that the sunken section of the tub bottom is an integral portion offset from the plane of said bottom and is of substantially the same thickness as the remaining part thereof.

40 In this recess in the bottom 13, a filling 14 of non-slip, waterproof material, such, for example, as cement having an abrasive or adherent content to prevent slipping, is permanently secured and sealed so as to make a substantially integral structure with the tub, this filling 14 being preferably set so as to lie level with and form a continuation 45 of the bottom section 12. Anti-slip tiles can, of course, be substituted for the cement filler, if desired.

50 Obviously, ornamental effects can be worked out in both the cement or tile, non-slip filler, to give pleasing designs.

As shown in Figure 2, the waste or drain outlet 15 will extend upwardly and be fixed in the bottom 13 in any suitable or usual manner, and preferably, as shown in Figures 1 and 2, the filler 14, mounted in the recess of the bottom 13, will not extend as far as the waste or drain outlet 15, so that the waste or drain outlet can be secured

to the bottom section 12 of the tub in the usual manner and without disturbing the filler.

This type of tub, with the permanently secured and sealed waterproof filler, provides a completely sanitary job, as distinguished from those arrangements which contemplate the use of a loose, removable, non-slip mat, beneath which drippings will collect and stand.

The arrangement is such that the job, when completed, becomes an integral tub structure 10 which may be produced completely by the manufacturer and sold ready for installation, and it lends itself readily to decorative schemes and color combinations.

15 It will be observed that the outer wall or 10 apron 11 of the tub stands substantially vertical, and since there is an appreciable distance between the inner and outer walls of the tub, one leaning over and using the tub must necessarily stand back a considerable distance in a rather 20 awkward position. To overcome this difficulty, I have inclined the lower portion 16 of the apron 11 inwardly through a portion of its length, so as to give a substantial recess, contiguous to the floor, and a person standing by the tub is enabled 25 to stand closer, by reason of the toes of the feet extending into the recess formed by the inclined portion 16, and eliminate the awkward position ordinarily assumed where the apron 11 extends directly to the floor, as indicated in dotted lines 30 in Figure 1. When a portion only of the apron is inclined inwardly, a more pleasing and finished effect is given.

Such variations from the construction herein shown and described as are within the skill of a 35 mechanic may, of course, be made without departing from the range of my invention.

I claim:

1. A one-piece metal bath tub having an integral portion of its bottom offset from the plane of 40 the bottom and of substantially the same thickness to provide a recess, and a non-slip waterproof filling in said recess.

2. A bath tub having an apron extending in a substantially vertical plane, the lower portion of 45 the apron being recessed inwardly and downwardly to the floor to provide a space of sufficient area to accommodate a foot of a person leaning over the tub.

3. A bath tub having an apron extending in 50 a substantially vertical plane, the lower portion of the apron having a longitudinally extending space formed therein for the reception of the feet of a person leaning over the tub, said space being formed by an inwardly and downwardly 55 recessed portion of the apron having its lower edge resting on the floor.

ROBERT MUELLER.
